UNITED STATES PATENT OFFICE.

EWELL E. FOWLER, OF EAST POINT, GEORGIA, ASSIGNOR TO UNDERWOOD TYPE-WRITER COMPANY, OF NEW YORK, N. Y., A CORPORATION OF DELAWARE.

TYPEWRITING MACHINE.

Application filed October 7, 1924. Serial No. 742,117.

This invention relates to typewriting machines, and more particularly to a card-guiding device arranged at the front of the platen and close to the type-bar guide.

5 One feature of the invention is the provision of means for preventing the leading edges of forms or work-sheets from rubbing against the ribbon-vibrator or type-bar guide while being introduced into the machine and brought up to typing position.

10 Another feature is the provision of means for guiding the side edges of cards or stiff work-sheets away from the type-bar guide and ribbon-vibrator when the carriage is moved laterally, thus preventing the edges of the sheets from fouling the type-bar guide or coming into contact with the ink-ribbon.

15 A further feature includes means for holding the work-sheets toward the platen, so as to prevent the upper-case type from "shadowing" or printing upon the work-sheets when the ribbon has been shifted to bring the lower portion thereof to the printing line.

20 Other features and advantages will hereinafter appear.

In the accompanying drawings,

25 Figure 1 is a fragmentary view, in front elevation, of a platen and a type-bar segment of a typewriting machine, showing my wire-guide in position thereon.

30 Figure 2 is a transverse section through the machine on a plane through one of the shanks of the wire-guide, and illustrates the introduction of a work-sheet into the machine.

35 Figure 3 is a transverse section on the line 3—3 of Figure 1, and shows a work-sheet brought up to position between the right-hand wing-scale and the platen.

40 Figure 4 is a top plan of the wire-guide forming the present invention.

45 Figure 5 is a front view of the wire-guide; and Figure 6 is a side elevation thereof.

50 I have illustrated my wire-guide as applied to an Underwood standard typewriting machine in which the usual type-bar segment 10 is suitably secured to a segment-bracket 11 just in front of and below a platen 12. Feed-rolls 13 and 14 normally bear against the under surface of the platen and may be moved away from said platen by means of a suitable release key (not

shown), but which is well understood in the art. The platen is mounted upon an axle 15 having bearings in the right and left ends 16 and 17 of a platen-frame 18, and the latter may be mounted as usual to shift up and down to the different case positions. A paper-table 18' is provided upon the frame 18, and the platen 12 may be rotated by hand-wheels mounted on the ends of the platen-axle, as indicated at 12' in Figure 1. The letter "T" indicates type which are driven to the platen by the usual key-levers and connections (not shown). Wing-scales 19 and 20 are pivoted upon suitable brackets 21 and 22, which are secured to the type-bar segment 10 by means of screws 23, and springs 23' are effective to yieldingly hold the wing-scales 19 and 20 toward the platen. A type-bar guide 24 is carried by the type-bar segment 10, and a ribbon-carrier 25 is vibrated to throw a ribbon 26 to the printing line of the platen.

55 Thus far the mechanism described is that which has heretofore been used, and its description here is given simply for a clear understanding of the manner in which the device forming the present invention, now to be described, is associated, for the purpose of causing work-sheets to clear the type-bar guide and ribbon-carrier during operation of the machine.

60 In the upper edge of the segment 10, I provide two oppositely-disposed sockets 27 which receive the lower ends of parallel bows or shanks 28 of a bifurcated wire-frame or guide 29. The shanks 28 extend upwardly and are formed with offsets or bends 30 which are directed upwardly and inwardly towards the platen 12, and then rebent at 31 to form inclined portions 32 directed upwardly and away from the platen, and it 65 will be noted, by referring to Figures 1 and 5, which show front views of the wire-guide, that the inclined portions 32 are also bent outwardly toward the edges 19' and 20' of the wing-scales. The upper portion 70 of the wire-guide forms a tongue 34 having side members 35 which are directed upwardly and inwardly toward each other and terminate in the flattened tip 36, and these side members form with the portions 32 a pair 75 of oppositely-directed tongues 33, the tips of which lie closely adjacent the side edges 80 of the wing-scales. The upper portion 85

With particular reference to Figures 2 and 3, it will be seen that the side members 35, forming the upper portion of the tongue 34, slant inwardly toward the platen and are substantially tangent thereto. The tongues 33 of the wire-guide are disposed slightly to the front of the plane of the wing-scales 19 and 20, as clearly shown in Figure 3, and the purpose of such positioning will appear later in the description. The wire-guide 29 is preferably formed of spring-wire and the resiliency of the bows or shanks 28 effectively retains said shanks within the sockets 27, so as to secure the wire-guide in position upon the segment 10. In Figure 2 a plurality of interleaved work-sheets "S" have been inserted beneath the platen, and it will be noted that as the sheets emerge from the under side of the platen, the leading edges 20 of the sheets engage the inclined portions 32 of the wire-guide 29, and are thereby deflected upwardly toward the side members 35, which then direct the sheets upwardly and rearwardly toward the platen.

Figure 3 illustrates the position of work-sheets which have been inserted under the platen and brought up to position beneath the wing-scale 19, and properly adjusted in a collating chute 37, and the feed-rolls 13 and 14 returned to effective position to enable the sheets to be run to the printing line. Now, when the carriage is moved laterally during operation of the machine, the side edges of the work-sheets will be deflected away from the type-bar guide and ribbon, due to the fact that as the edges of the sheet move from under the wing-scales in either direction of travel of the carriage, said edges immediately come under the influence of the tongues 33 of the wire-guide which deflect the sheet-edges toward the platen sufficiently to clear the type-bar guide and ribbon-vibrator. Thus, it will be seen that the wire-guide forms, in effect, a continuation of the wing-scales, so that any tendency of the work-sheets to spring away from the platen, and become caught against the type-bar guide, or rub against the ribbon, is entirely overcome. The tongue 34 is also effective to hold the work-sheets toward the platen, as indicated by dot-and-dash lines in Figure 2, and thus prevents the upper-case type from "shadowing" or printing upon the work-sheets when the ribbon is shifted to upper position.

Variations may be resorted to within the scope of the invention, and portions of the improvements may be used without others.

Having thus described my invention, I claim.

1. In a typewriting machine, in combination, a platen, a segment having sockets therein, a type-bar guide, and a wire-guide having shanks received in said sockets, the upper portion of said wire-guide being bent

outwardly and upwardly, and then rebent inwardly and upwardly with respect to said platen, so that a work-sheet, inserted from the rear of the machine and beneath the platen, is deflected upwardly and away from said type-bar guide, and thence upwardly and inwardly toward the platen. 70

2. In a typewriting machine, in combination, a carriage, a platen, a type-bar segment, a type-bar guide, a ribbon-vibrator associated therewith, wing-scales positioned on opposite sides of said type-bar guide, and a wire-guide disposed about said type-bar guide and including a pair of oppositely-directed tongues located slightly to the front of the plane of said wing-scales, and having portions thereof inclined toward the platen, so that the side edges of work-sheets, moved laterally with the carriage, ride over said inclined portions, causing the sheets to be 85 guided toward the platen sufficiently to clear said type-bar guide and ribbon-vibrator. 80

3. In a typewriting machine, in combination, a carriage, a platen, a type-bar segment, a type-bar guide, a ribbon-vibrator, wing-scales disposed on opposite sides of said type-bar guide and having their inner side edges opposite said ribbon-vibrator, and a wire-guide disposed about said type-bar guide and including a pair of oppositely-directed tongues terminating closely adjacent the inner side edges of said wing-scales and slightly to the front of the plane of said wing-scales, said wire-guide having portions thereof bent and inclined toward the platen, so that the side edges of work-sheets, moved laterally with the carriage in either direction, ride over said inclined portions, deflecting the sheets toward the platen sufficiently to clear said type-bar guide and ribbon-vibrator. 100

4. In a typewriting machine, in combination, a carriage, a platen, a type-bar segment having a pair of sockets therein, a type-bar guide, a ribbon-vibrator, wing-scales disposed on opposite sides of said type-bar guide and having their inner side edges opposite said ribbon-vibrator, and a wire-guide forming a frame about said type-bar guide and ribbon-vibrator, said wire-guide including shanks received in said sockets, and having its upper portion bent to form a pair of oppositely-disposed tongues terminating at points closely adjacent the inner side edges of said wing-scales and slightly to the front of the plane thereof, said tongues having portions thereof bent so as to be inclined toward the platen, said wire-guide also including a vertically and rearwardly disposed tongue extending above the printing line of the platen, so that the side edges of work-sheets, moved laterally with the carriage in either direction, ride over said inclined portions and under said second-named tongue, so as to direct the work-sheets rear- 125

wardly toward the platen, and thereby prevent said sheets from engaging the type-bar guide or rubbing against the ribbon-vibrator.

5. In a typewriting machine, in combination, a carriage, a type-bar segment, a type-bar guide, wing-scales disposed on opposite sides of said type-bar guide, and a wire-guide about said type-bar guide, and forming in effect a continuation of said wing-scales, whereby to direct the side edges of work-sheets toward the platen, when the carriage is shifted laterally in either direction.

6. In a typewriting machine, in combination, a platen, a segment, a ribbon-vibrator, type-bars including upper and lower case type, wing-scales disposed on opposite sides of said ribbon-vibrator, and a wire-guide carried by the segment and including a pair of oppositely-directed tongues disposed adjacent the front of the platen and forming in effect a continuation of said wing-scales, whereby to guide the side edges of work-sheets away from said ribbon-vibrator, when the carriage is shifted laterally, and also to hold said work-sheets toward the platen to prevent the upper-case type from printing

upon said sheets, when the ribbon-vibrator is shifted to upper position.

7. In a typewriting machine, in combination, a platen, a type-bar guide, wing scales 30 on opposite sides of said type-bar guide, and means co-operating with said wing-scales, whereby to engage the side edge of a work-sheet as it is moved laterally with the platen from under said wing-scales, and guide said 35 edge toward the platen and away from said type-bar guide so as to clear the latter.

8. In a typewriting machine, in combination, a platen, a segment having sockets therein, a type-bar guide, a ribbon-vibrator, 40 wing-scales on opposite sides of said type-bar guide and ribbon-vibrator, and a wire-guide, including shanks received in the sockets, the upper portion of said wire-guide being bent to form a pair of oppositely-directed tongues and so positioned with relation to the wing-scales that the side edges of work-sheets, moved laterally with the platen, engage said tongues and are thereby deflected toward the platen so as to clear the 45 type-bar guide and ribbon-vibrator.

EWELL E. FOWLER.
